United States Patent Office

Des. 181,646
Patented Dec. 10, 1957

181,646

HOLDER FOR BARBER EQUIPMENT

Abraham T. Hashem, Cheektowaga, N. Y.

Application April 3, 1957, Serial No. 45,569

Term of patent 14 years

(Cl. D4—3)

Fig. 1.

Fig. 2.

Fig. 3.

Fig. 6.

Fig. 5.

Fig. 1 is a perspective view of a holder for barber equipment embodying my new design, this view being taken from the front to the left of the holder.

Fig. 2 is a top plan view thereof.

Fig. 3 is a front elevational view thereof.

Fig. 4 is a bottom plan view thereof.

Fig. 5 is a side elevational view, the opposite side view being substantially the same.

Fig. 6 is a rear elevational view thereof.

I claim:

The ornamental design for a holder for barber equipment, substantially as shown and described.
